(57) **CLAIM**

The ornamental design for a cell phone base station interface for LAN phones, as shown and described.

DESCRIPTION

FIG. 1 is a front elevational view of a cell phone base station interface for LAN phones showing my new design;

FIG. 2 is a rear elevational view thereof;

FIG. 3 is a right side elevational view thereof;

FIG. 4 is a left side elevational view thereof;

FIG. 5 is a top plan view thereof; and,

FIG. 6 is a bottom plan view thereof.

The broken line showings in the figures are for illustrative purposes only and are hereby disclaimed as forming no part of Applicant's claimed invention.
